UNITED STATES PATENT OFFICE.

CARL STEINBERG, OF NEW YORK, N. Y.

STRAW HAT.

Application filed January 19, 1927. Serial No. 162,167.

- 5 My present invention relates generally to straw hats and more particularly to the type of straw hat which has a relatively rigid crown and brim portions, each predeterminedly shaped in advance and associated therewith so as to form a stiff type of straw hat, as distinguished from hats of the leg-horn or Panama type, and which has an intermediate flexible portion.
- 10 Straw hats of the character disclosed herein and in connection with which my invention is primarily to be employed, consist of a crown and a brim, each made up of straw braid arranged spirally and secured together in any preferred or desired manner. The body and rigidity is given to the assembled braid forming a crown and a brim by means of any preferred filling, sizing or adhesive material.
- 15
- 20 The object of the present invention is to provide a straw hat having a flexible part interconnecting the crown and brim, so constructed as to provide permanency and wearing qualities to the flexible part.
- 25 Other objects of my invention will either clearly appear or be pointed out hereinafter.

I have illustrated in the drawings and described in the specification, a novel manner of reinforcing the more flexible portions of 30 the brim and the crown so as to give all the advantages of flexibility without the accompanying disadvantages. This reinforcement is in the form of a strip secured to the spirally extending braid at or 35 beyond the point of demarcation of the crown and extending spirally downwardly to the lower edge of the crown, and then outwardly helically, exteriorly of the crown to the point of demarcation of the brim, or 40 to a point beyond. This strip is preferably, although not necessarily, in the form of braid narrower than that of which the hat is made, and of closer weave so as to more effectively serve the purposes for which it is 45 intended, as will more fully appear hereinafter.

In practice, the reinforcing strip may be secured to the braid before the winding thereof into the form of a hat and where this 50 is done, such as by stitching the two together, for any predetermined or desired length, there is in effect, formed a composite braid, that is a unit consisting of the braid and the strip for such preferred length. Where 55 the brim is made of two layers of straw braid, as in the preferred embodiment, I

have found it advisable to make each layer substantially in the manner described with respect to one layer, except that the layers are so positioned that the reinforcements are 60 on opposite sides of the brim and securing the reinforcing strips in position by stitches so that separation of the brim layers is thus prevented.

While I have illustrated in the herein described embodiment, a continuous strip forming both the spiral reinforcement for the crown and the helical reinforcement for the brim, yet it will be understood that this strip may be continued and made up of 70 separate sections, giving the effect of continuous strip.

For the attainment of these objects and such other objects as may hereinafter appear or be pointed out, I have illustrated in 75 the drawings, one embodiment of my invention, wherein:

Fig. 1 is a perspective view of a straw hat embodying my invention with a portion of the band broken away so as to expose the 80 underlying construction;

Fig. 2 illustrates a portion of the brim on an enlarged scale;

Fig. 3 illustrates a portion of my composite braid or unit showing a formation of 85 the same; and

Fig. 4 is an elevational view of the construction shown in Fig. 1;

Referring to the drawings, it will be seen that the straw hat comprises a crown portion 10 and a brim portion 11. Between the crown and the brim at points designated by "a" and "b" of Fig. 1, is the flexible or intermediate section connecting the upper part of the crown and the outer edge of the 90 brim. The straw hat will therefore be seen to consist of three parts: first, the upper part of the crown; second, the intermediate or junction portion; and, third, the outer edge of the brim. The first and third portions are constructed of relatively wide braid of comparatively loose weave having one serrated edge 16 and one smooth edge 17. In forming the hat from this braid, it is usual to start at the center of the crown indicated at 19 and thereupon coiling said braid spirally downward toward the band portion so as to have the adjacent coils superposed one upon the other, that is, each convolution is laid with its smooth edge 100 under the serrated edge of the preceding convolution. These coils are then secured to

form the portions of the hat in any preferred or desired manner by stitching. It is usual to stitch the crown and brim portions by a concealed stitching machine so that the stitch will not be apparent to the observer.

The intermediate or junction portion differs from the other two sections in these respects: Instead of a simple straw, it is a composite straw and instead of overlapping the smooth edge of one convolution by the serrated edge of the previous convolution in this third section, the composite braid is so wound that the smooth edge of one convolution overlaps the serrated edge of the previous convolution.

By referring to Fig. 3, the construction of this composite strip will be clearly seen. It comprises a braid similar in all respects to the braid of the crown and brim portions, but along the smooth edge thereof, is placed in overlapping position the reinforcing strip 20 in such a manner as to provide the overhanging flange portion 18 which consists of that portion of the reinforcing strip which does not overlap the smooth edge of the braid. These two are then united along this overlapping edge by a row of stitching 14 which serves to unite the two in a firm manner and to permit of the use of the composite braid as a unit in the manner to be brought out.

As stated above, the coiling of the crown portion progresses downwardly to the point "a" in Fig. 1. At this point, the braid terminates or comes to an abrupt end in the preferred embodiment as shown at 12 in Fig. 4. At this point, the composite strip is used to continue the hat construction and to provide the intermediate portion above referred to. The composite strip instead of being placed with its smooth edge, underlying the serrations of the previous convolution, is so positioned that the smooth edge is placed in overlapping relation to the serrated edge of the previous convolution and the overhanging flange portion of the composite strip overlies the adjacent portion of the subjacent strip. The composite braid is coiled in this manner for any preferred or desired length, preferably until approximately the point "b" in Fig. 1 is reached. This point is indicated at 13 in Fig. 2, where the composite braid terminates. At the point 13, the simple braid is again used and coiled to form the outer edge of the brim in the same manner described with respect to the upper portion of the crown.

It will therefore be apparent that from the point 13 onward to the outer edge of the brim, the braid again is positioned with the smooth edge underlying the serrated edge of the previous convolution.

In the intermediate portion joining the crown and the brim, as stated, the com-

posite braid is used and as also stated, it is so positioned that the smooth edge of the braid overlaps the underlying serrated edge of the previous convolution. The extending flange portion naturally occupies a position referring to Fig. 2 slightly above the point at which the two braids overlap, that is, the extending overhanging flange of the composite braid overlaps an additional adjacent portion of the underlying serrated edge of the previous convolution, and is united thereto by a second line of stitching as indicated at 15. The two rows of stitching in this intermediate portion are preferably made with an exposed or through-and-through stitch in contra-distinction to the concealed stitch used in the crown and brim. By the use of these two rows of stitching, the teeth of the serrations are formally held down and reinforced so that less sizing can be used to attain the desired flexibility, and yet a strong permanent flexible construction, attained.

In the usual manufacture of straw hats, the three portions already described, are made in separate rooms on separate machines although such is not necessarily so.

It will be understood that the type of braid to which the reinforcing strip is attached in overlapped relation, may be of any preferred type, such as being provided with either or both edges, smooth or serrated.

It will be clear from the above that where the brim of the hat is of the double layer type, a fourth section may be made which is similar to the brim portion already described, that is, it has the outer edge made in the usual manner and the inner portion made of the composite type of braid to provide an exactly analogous construction. This fourth member, when such is used, is then associated with the brim portion already mentioned in such relation that the two layers are placed back to back, whereby reinforcement is obtained on both sides of the brim and the rows of stitching on the aforementioned reinforcing strips, so unite the two layers, that they are prevented from separation.

Having thus described my invention, what I claim as new and desire to secure by Letters Patent is:

1. A straw hat comprising a crown part, a brim part and an intermediate interconnecting part comprising overlapped, contacting, unconnected braids with a pliant strip covering the overlapped edge and connected at its opposite edges with both braids.

2. A straw hat comprising a crown part and a brim part composed of overlapped connected braids, an intermediate interconnecting part composed of unattached braids, overlapped in opposite direction into contact, and an additional different type of

braid spanning the overlap and concealing one of the edges and connected at its opposite edges to both of said braids.

3. A straw hat comprising a crown part and a brim part composed of braids overlapped in the same direction and connected, an intermediate interconnecting part composed of unattached contacting braids overlapped in the opposite direction, and an additional relatively finer and pliant braid spanning the overlap and concealing one of

the overlapping edges, said pliant braid being attached at its opposite edges to the overlapped braids.

4. In a straw hat, a part consisting of overlapped, unattached contacting braids, and a pliant strip spanning the overlap and attached at its opposite edges to both of said first mentioned braids.

In witness whereof, I have signed this specification, this 4th day of January, 1927.

CARL STEINBERG.
